(57) CLAIM

I claim the ornamental design for a necktie, as shown and described.

DESCRIPTION

FIG. 1 is a front elevation view of a necktie showing my new design;

FIG. 2 is a right side elevation view thereof, the left side being a mirror image of the right; and,

FIG. 3 is a rear elevation view thereof.

1 Claim, 1 Drawing Sheet

FIG. 1

FIG. 3
